UNITED STATES PATENT OFFICE

CARLETON G. EATON, OF WALTHAM, MASSACHUSETTS, ASSIGNOR TO A. M. EATON PAPER COMPANY, OF BOSTON, MASSACHUSETTS, A CORPORATION OF MASSACHUSETTS

DEVICE FOR POSITIONING STRING HANDLES ON PAPER BAGS

Application filed March 9, 1929. Serial No. 345,748.

This invention relates to the manufacture of bags and more particularly to mechanism for positioning and securing string handles on paper shopping bags.

5 In the manufacture of paper shopping bags it has been common practice to cut string to suitable length and position and hold the same upon the bag manually while holding the bag in suitable position in a 10 riveting machine for securing the string to the bag. This has involved a great deal of manual labor and large item in the cost of producing such bags. Moreover, the use of this method has delayed production and 15 limited the productive capacity of the factory. When the handle and bag are positioned manually relative to each other in this manner the ends of the handle often extend different distances from the top edge 20 of the bag and the rivets often are positioned unevenly. These occurrences have been frequent when it has been attempted to speed up production.

It is the object of the present invention 25 to provide a low cost mechanism which will eliminate this manual labor to a large extent and thereby lower the cost of production of such bags and make possible the production of bags having a neat uniform appearance.

30 The invention will be more clearly understood from the following description in conjunction with the accompanying drawings, in which:

Fig. 1 is a perspective view of one type of 35 bag produced by use of the mechanism of the invention;

Fig. 2 is a front elevational view partly in diagram of a device embodying the invention.

40 Fig. 3 is a sectional view taken on the line 3-3, Fig. 2.

Fig. 4 is a sectional view taken on the line 4-4, Fig. 2, certain of the parts being broken away.

45 Figs. 5, 6, and 7 are views similar to Fig. 4 showing the different positions of the various parts of the device during operation.

Before explaining in detail the present invention, it is to be understood that the invention is not limited in its application to

the details of construction and arrangements of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention beyond the terms of the several claims hereto appended as considered in view of the prior art and the requirements thereof.

The invention is directed particularly to the manufacture of paper bags one form of which is illustrated in Fig. 1. In the manufacture of the bag 10 illustrated, sheet paper is shaped to tubular form and one end closed to form the bottom of the bag. Preferably a strip of gummed paper tape 11 is moistened upon its gummed side and secured to the bag near its open end on diametrically opposite portions and extending downwardly below the point of attachment of the string handles 12. The top edge of the open end then is folded downwardly to provide flaps 13. The handles 12 are secured as illustrated by upper and lower fasteners 80 and 81 respectively.

The present invention is directed particularly to mechanism for positioning the bag 80 10 and handles 12 relatively in an operative relation to a suitable machine for setting the fasteners to secure the handles to the bag.

A device suitable for this purpose, as illustrated in the accompanying drawings, 85 may comprise a frame F including front upright members 15 and rear upright members 16. The members 15 and 16 are connected by an intermediate cross member 18 and top cross members 19. A plate 20 is formed integrally or secured in any suitable manner at the upper ends of the uprights 15 and 16 and is provided at its opposite side edges with suitable guides 23 for a movable slide 24. The plate 20 is provided with a 90 forwardly extending apron 26 upon which a template 27 is mounted at a point spaced rearwardly from the forward edge of the apron. The template 27 is provided with an inner surface 28 of the desired shape of 95 100

the string handle. A similarly shaped surface 29 is provided upon the forward edge of the slide 24 which is adapted to cooperate with the surface 28 to position and shape a length of string.

Suitable means is provided also for positioning the top edge of a paper bag relative to the template 27 after the string has been shaped thereagainst. For this purpose, in the embodiment of the invention illustrated, arms 30 extend forwardly from the slide 24 and each is provided at its forward edge with a bag positioning surface 31 adapted to engage the top edge of the bag when the slide is moved to its forward position. If desired, the forward edge of the template 27 may also be provided with a bag positioning surface 33. The plate 20 of the frame is positioned with the apron 26 in operative relation to suitable fastener setting devices, generally indicated at 35 and 36 which may be of the usual construction commonly employed for forming and inserting fasteners in a paper bag.

25 The slide 24 is provided with rearwardly extending spaced lugs 40 adapted to receive therebetween one arm 41 of a bell crank fixed upon a shaft 45 which extends between and is rotatably mounted in the intermediate cross member 18. The free end of the arm 41 is provided with an elongated slot 42 adapted to receive a pin 43 extending between the lugs 40. The other arm 46 of the bell crank is connected to one end of a 35 rod 47, the other end of which is connected to a foot treadle 48. The foot treadle 48 is pivotally mounted upon a shaft 49 extending between the rear uprights 16 and is held in raised position by a spring 50 connected at one end to the treadle 48 and at its other end to the frame.

A suitable mechanism is provided for feeding string automatically to the handle positioning mechanism and cutting the string to the desired length. With this in view a hollow tube 65 (see particularly Fig. 4) is secured to the frame and is adapted to receive the free end of string 66 extending from a supply roll (not shown). 50 A sleeve 68, slidably mounted on the tube 65, has pivoted thereto at 14 a pawl or detent 70 the point *a* of which passes through a longitudinal slot 71 in the tube 65 and is adapted to engage the string and feed it into the machine during the operation thereof. The sleeve 68 carrying the pawl 70 is connected with mechanism for moving the same an amount corresponding to the length of string in each handle 12. As shown, the 55 sleeve 68 is connected by a strap 72 with a relatively large pulley 75 rotatably mounted on a stud 76 projecting from the frame. A relatively small pulley 78 preferably formed integrally with the pulley 75 is connected 60 by a strap 79 to a stud 8 secured to the

slide 24. The relation of the diameters of the pulleys 75 and 78 is such that the string 66 is fed an amount equal to the length of string in each handle 12 as the slide 24 moves from its forward position to its rear position. The arrangement is such that as the slide 24 is retracted or moved rearwardly, the pawl 70 is moved first into engagement with the string 66 and then forwardly to carry the string across the top surface of the plate 20 to the position shown in Fig. 4. As the slide 24 is moved forwardly into operative position, the pull on the straps 79 and 72 is released and the pawl 70 is first disengaged from the string and then moved rearwardly by a spring 100 secured at one end to said pawl and at the other end to the outer end of the tube 65. The mechanism for cutting the string may comprise an arm 55 secured to the shaft 45 near one end thereof and is connected to one end of a rod 56, the other end of which is connected to one end of a lever 57 pivotally mounted on a lug 58 depending from the plate 20 of the frame. The other end of the lever 57 is pivotally connected with a knife 60 mounted to move in a guideway in the frame. The knife 60 is arranged to cooperate with a cutting edge which may be provided on the forward end of one of the guides 23.

In the operation of the device the foot treadle 48 is moved downwardly thereby actuating the arm 41 of the bell crank through the connecting rod 47 to move the slide 24 forwardly. At the same time the arm 55 is actuated to operate the knife 60 to cut the string 66 to the desired length. As the slide 24 moves forward the piece of string which has been cut to length is moved forwardly and shaped around the surface 28 of the template 27 with the free ends of the string extending forwardly from the latter in parallel relation as shown in Fig. 5. The top surface of the bag 10 is then placed against the positioning surfaces 31 on the forward ends of the arms 30 so that one side of the bag 10 rests upon the ends of the string or between the string and the apron 26 depending upon whether it is desired to secure the string to the outer or inner surface of the bag. The fastener setting devices 35 and 36 are then operated to insert the top fasteners 80 as shown in Fig. 6. The foot treadle 48 is then released and the spring 50 retracts the slide 24 to the position shown in Fig. 7 and at the same time causing the string 66 to be fed across the plate 20 to the position shown in Fig. 4. The top edge of the bag 10 now is placed against the positioning surface 33 upon the forward edge of the template 27 and the fastening devices 35 and 36 operated to insert the lower fasteners 81 as shown in Fig. 7. It will be noted that the positioning sur-

faces 31 are spaced forwardly from the forward edge of the template 27 when the slide is moved to its forward position thereby permitting the bag and handle 12 to be moved relatively to permit the removal of the handle 12 from the template 27 when the slide 24 is retracted.

What I claim is:

1. The combination with means for securing a string handle to a bag, of a frame, a template on said frame for positioning said handle, a member for positioning a bag in a predetermined relation to said template, and means for moving one of said members relative to another to permit the removal of said handle from said template after the former has been secured to the bag.

2. The combination with means for securing a string handle to a bag, of a frame, a template on said frame for positioning a string handle, and a bag positioning member movable towards and away from said template.

3. The combination with means for securing a string handle to a bag, of a frame, a template on the frame, a slide movable on the frame adapted to cooperate with said template to position a string handle, means for positioning the top edge of a bag relative to said template, and means for moving the slide towards and away from the template to position a string handle extending therefrom substantially parallel.

4. The combination with means for securing a string handle to a bag, of a frame, a template on the frame, a slide movable to cooperate with the template to position a string handle, a movable member for positioning a bag with its top edge in spaced relation to said template, and means for moving the slide towards and away from the template to position a string handle.

5. The combination with means for securing a string handle to a bag, of a frame, a template on the frame, a slide movable to cooperate with the template to position a string handle, arms projecting forwardly from said slide for positioning a bag with its top edge in spaced relation to said template when said slide is in its forward position, and means for moving the slide towards and away from the template to position a string handle.

6. The combination with means for securing a string handle to a bag, of a frame, a template on the frame, a slide movable to cooperate with the template to position a string handle, arms projecting forwardly from said slide for positioning a bag with its top edge in spaced relation to said template when said slide is in its forward position, means for moving the slide towards and away from the template to position a

string thereagainst and means for positioning the bag when the slide is retracted.

7. The combination with means for securing a string handle to a bag, of a frame, a template on said frame for positioning a string handle, a member for positioning a bag in a predetermined relation to said template, means for moving one of said members relative to another, and means actuated by said movable member for feeding string adjacent said template and cutting the same to a predetermined length.

8. The combination with means for securing a string handle to a bag, of means for positioning a bag and string handle relatively including a slide, means for moving said slide, and means movable as said slide moves away from said handle for feeding string to said positioning means and cutting the same to a predetermined length.

9. The combination with means for securing a string handle to a bag, of a frame, a template on the frame, a slide movable to cooperate with the template to position a string handle, arms projecting forwardly from said slide for positioning a bag with its top edge in spaced relation to said template when said slide is in its forward position, means for moving the slide towards and away from the template to position a string thereagainst, and means operable as the slide is retracted for feeding string from a supply between said slide and template and for cutting the string to the desired length.

In testimony whereof I affix my signature.
